UNITED STATES PATENT OFFICE.

JOSEPH CZERWINSKI, OF CHICAGO, ILLINOIS.

BELT-BUCKLE.

1,385,865.

Specification of Letters Patent.

Patented July 26, 1921.

Application filed April 11, 1921. Serial No. 460,348.

To all whom it may concern:

Be it known that I, JOSEPH CZERWINSKI, a citizen of the Republic of Poland, and a resident of the city of Chicago, in the county 5 of Cook and State of Illinois, have invented certain new and useful Improvements in Belt-Buckles; and I do hereby declare that the following is a full, clear, and exact description of the same, reference being had to the accompanying drawings, and to the numerals of reference marked thereon, which 10 form a part of this specification.

This invention relates to buckles of the sort ordinarily worn with belts.

15 It is an object of this invention to provide a buckle which shall be readily secured in place and shall maintain its grip upon the belt without working loose.

It is a further object of this invention to 20 provide a buckle which will not materially lessen its grip upon the belt through wear due to repeated fastening and unfastening of the buckle.

It is a further object of this invention to 25 provide a buckle which is readily fastened and will not become accidentally unfastened.

It is a further object of this invention to provide a buckle with a pair of lugs which shall act to yieldingly retain the fastening 30 part of the buckle in fastening position.

It is a further object of this invention to provide a buckle which can be adjusted for use with belts of different thicknesses.

It is a further object of this invention to 35 provide a buckle of the class indicated which shall not depend upon motion past a dead center to render secure the grip of the buckle upon the belt.

Other and further important objects of 40 this invention will be apparent from the disclosures in the specification and the accompanying drawings.

The invention (in a preferred form) is 45 illustrated in the drawings and hereinafter more fully described.

On the drawings:

Figure 1 is a front view of the buckle secured in place upon a belt.

Fig. 2 is a section upon the line 2-2 of 50 Fig. 5.

Fig. 3 is an edge view of the buckle apart from the belt.

Fig. 4 is a section upon the line 4-4 of 55 Fig. 3.

Fig. 5 is a rear view of the buckle attached to the belt.

Fig. 6 is an enlarged view of a lug on the side of the buckle.

As shown on the drawings:

The buckle has a front plate 1 which may 60 have ornamentation of any desired kind. The two edges of this plate are turned up as shown at 2 to provide a housing for the belt and the working parts of the buckle. Mounted in the side walls 2 is a pivot pin 3. 65 The ends of this pin are secured in the walls in any convenient manner, as for example by being upset.

The movable fastening member or lever 5 of the buckle consists of a piece of sheet 70 metal bent to form a lever having two arms 6 and 7. The portion of this lever between these arms is bent to go around the pin 3 as shown at 8. At one or more places in this part of the buckle there are strips cut away 75 from the rest of the lever in order that they may pass upon the opposite side of the pin 3 as illustrated at 9. The arm 6 of the lever is straight for most of its length but near the pin 3 it is bent forming an angle 10 so 80 that that portion nearest the pin is approximately parallel to the arm 7. The pin 3 is thus housed within a U-shaped part of the member 5. The outer end of the arm 6 is provided with a slotted portion 11 for the 85 passage of the looped end of the belt. The arm 7 is somewhat longer than the analogous part of similar buckles heretofore used, so that it is not possible for the arm 7 to pass beyond a dead center to a position where the 90 pressure of the belt would tend to keep it in fastening position. The contact of the arm 7 with the belt will stop it before the dead center is reached.

Upon the side walls 2 at the end and 95 where the arm 6 emerges is provided a pair of lugs 12. The lugs are bent inward from the side walls 2 so that they are substantially parallel to the front wall 1 as shown in Fig. 4. The edges of the lugs are not parallel to the line of bending and are not straight; they are composed of a long and gentle slope 13 and a short abrupt slope 14, the first extending away from the other toward the side walls, as best illustrated in 100 Fig. 6.

The loop on the belt is passed through the slot in the part 11 and secured by any conventional means. The other end of the belt is passed through the housing between the 110 front plate 1 and the arm 7. While inserting this end of the belt the lever 5 is in its

purpose limiting the patent granted otherwise than necessitated by the prior art. 65

I claim as my invention:

1. In a buckle, an elastic housing, a clamping lever pivotally mounted in said housing, and lugs on said housing yieldingly engaging said lever whereby the accidental 70 displacement of said lever from clasping position is prevented.

2. A buckle comprising a housing of resilient sheet metal, a sheet metal clasping lever mounted in said housing, lugs on the 75 walls of said housing engaging the edges of said lever, the edges of said lugs being oblique to the sides of said housing and forming a smaller angle with the walls of the housing on the side of the lugs toward 80 the mounting of the lever than on the other side of said lugs.

3. A buckle comprising a housing of resilient sheet metal, a sheet metal clasping lever mounted in said housing, lug on the 85 walls of said housing engaging the edges of said lever, the edges of said lugs being oblique to the sides of said housing and forming a smaller angle with the walls of the housing on the side of the lugs toward 90 the mounting of the lever than on the other side of said lugs, the plane of said lugs being parallel to the plane of said lever.

4. In a belt buckle, a trough-shaped front plate, a clasping member pivotally mounted 95 in said trough, and lugs on the sides of said trough past which the clasping member must be sprung to bring the buckle to fastening position.

5. In a buckle, two parts pivotally connected together, a lug, one of said parts engaging the other part, and cam edges on said lug for permitting the last named part to be sprung past said lug, the portion of said edges contacted by the moving part when 105 traveling in one direction having a more gentle slope than the portion contacted by the moving part when traveling in the other direction.

6. In a belt buckle, a clasping lever comprising two arms extending on the same side of the fulcrum, one of said arms being longer than the other and being bent so that the portion of it nearest the fulcrum is parallel to the other arm and the remainder 115 of it makes an angle with first named portion, the apex of said angle being adjacent the end of the shorter arm.

In testimony whereof I have hereunto subscribed my name in the presence of two 120 subscribing witnesses.

JOSEPH CZERWINSKI.

raised or releasing position which is not illustrated in the drawings. When the belt has been tightened to the desired degree the lever is moved to the illustrated position by 5 pressing the arm 6 toward the front plate 1. This brings the arm 7 against the end of the belt 16 and at the same time forces the arm 6 between the lugs 12.

The side walls 2, being somewhat elastic, 10 yield to permit the passage of the member 6 between the lugs 12. The arm 6 may itself be somewhat yielding to facilitate this passage. The work of forcing the walls apart is rendered easy by the additional circumstance that the slope of the part 13 of the edge of the lug is very gentle. As the lever is forced past the lugs this edge acts as a cam to force the wall 2 outward and the edge of the arm 6 inward. The pull of the 15 20 looped end 15 of the belt on the arm 6 tends to keep the lever in the illustrated position. If any movement of the wearer of the belt should lessen the pull upon the belt so that there should be a tendency of the lever to depart from the illustrated position, the lugs 12 will prevent such motion, holding the lever to the illustrated position.

When it is desired to unfasten the belt the lever is positively moved to the unfastening position. To do this the arm 6 must be forced past the lugs 12 against the elastic force of the sides 2 and of the arm itself. Because the cam portion 14 of the edges of the lugs is steep, considerable effort is required in order to move the lever in this direction; consequently, accidental movement of the lever to releasing position is extremely unlikely.

Since the arm 7 does not go past the dead center in the fastening movement of the lever, the elasticity of the material of the lever will cause the arm 7 to effectively clasp the belt, even though repeated use of the buckle at the same spot on the belt should 40 45 50 55 60 65 70 75 80 85 90 95 100 105 110 115 120 wear the material of the end 16 so that it becomes thinner than when first used. Also the lever 5 may be made of some metal that is easily bent so that the angle the arm 7 makes with 6 can be changed from time to time, if desired, to accommodate a worn belt or to accommodate material of different thickness if the buckle is used upon a different belt. The metal of the lever 5 must not however bend so easily that it will fail to hold the belt firmly even after repeated use. The apex of the angle 10 forms a very convenient rest for a tool such as would be used in bending the arm 7 when such bending is desired.

60 I am aware that numerous details of construction may be varied through a wide range without departing from the principles of this invention, and I therefore do not
